UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

Application filed October 28, 1920. Serial No. 420,075.

My invention relates to an electric switch and particularly to a mechanically operated switch adapted to be associated with an automatic actuating mechanism of any suitable sort, connected for instance, with the mechanism of a washing machine. The object of my invention is to provide an improved construction of the switch body and operating connections adapted to the particular needs of an installation of this type and having certain features of improvement hereinafter described or shown in the accompanying drawing in which—

Fig. 1 is a plan view of a switch in which my invention is embodied in one form, and showing the switch cover opened to disclose the construction of the switch body and the arrangement of the switch mechanism therein.

Fig. 2 is a section on the line 2—2 Fig. 1. Fig. 3 is an exploded perspective of certain of the elements of the switch mechanism, and

Fig. 4 is a perspective of one of the combined wire and switch terminals.

In the construction illustrated, the switch base 5 comprises a block of insulating material such as porcelain, molded composition or the like, the top of which is recessed to afford a switch chamber 6 within which the switch mechanism and the associated terminals are arranged. The switch is designed to be mounted on an underlying support 7 of any suitable type and is accordingly pierced at opposite corners by counter-sunk apertures 8 through which the securing screws (not shown) pass into the support.

At its opposite corners the base is provided with tapped rivets 9 or the like into which take the small screws 10 by which the cover 11 is held in position upon the base. The latter is preferably provided with a marginal flange 12 within which the cover 11 sets flush. This cover as in the form shown is made from a plate of sheet metal lined on its inner face with a corresponding sheet 13 of insulating material, such as paper or fibre, secured to the metal plate 11 by rivets 14 arranged at the corners diagonally opposite the holes 15 through which the screws can pass. By making these rivets in the form of tubular eyelets, rivets may be arranged in all four corners of the cover and the screws 10 can pass through those registering with the tapped eyelets as in the base.

Mounted on ledges 16 at opposite sides of the switch chamber 6 are the combined wire and switch terminal plates 17 and 18 to which the bared ends of the lead wires 19 and 20 are attached in any suitable way, as by means of using binding screws 21. A wire entry aperture 22 is formed in one side of the base in communication with the channels 23 and 24 leading in opposite directions to the wire terminal plates. A barrier 25 separates the channels 23 and 24 from the switch chamber 6 and thus prevents the escape of wire beards into the chamber in region of the switch terminals and the switch mechanism. Each terminal plate is provided with an offset flange 26 lying at right angles thereto and carrying at its free end a switch terminal 27 or 28.

The switch mechanism is of the general type disclosed in the Anderson Patent No. 1,348,684 dated August 3, 1920, and comprises a frame having parallel plates 29 and 30 integral with foot pieces 31 and 32 extending between the same and bearing against vertical shoulders 33 at one side of the switch chamber. The side plate 30 is tapped at 34 to receive the securing screws 35 which take into the same through the base of the insulating body 5. The rocker 36 lies between the side plates 29 and 30 and is provided with outstanding bearing lugs 37 adapted to enter the bearing slots 38 formed in the upper margins of the frame plates. The switch yoke 39 straddles the frame and its legs are pivoted through the bearing slots 40 on the trunnion lugs 41 on opposite sides of the frame. The switch bar 42 carried by the yoke 39 makes or breaks contact with the switch terminals 27 and 28 and is thrown from one position to the other with a snap action by the switch spring 43 mounted on the split guide pin 44 one end of which engages in the aperture 44^a in the switch yoke, while it is supported and the spring 42 actuated by the web 45 of the rocker which works between the opposite sides of the split pin and bears against the washer 46 in the assembled condition of the parts.

To actuate the switch I provide a rod 47 having a cross pin 48 at one end adapted to engage in the notches 49 at one end of the rocker 36, the usual notches at the other end of the rocker being occupied by a spacing ferrule 50 and pin 51. The oscillation

of the rocker is limited by the impinge-
ment of the pins 48 and 51 against the
shoulders 52 and 53 at opposite sides of the
frame. The rod 47 extends out through
5 aperture 54 in the side of the casing, said
aperture being preferably in the form of a
slot extending to the upper face of the insu-
lating body so that the switch mechanism,
with the rod 47 assembled, may be intro-
10 duced as a unit into position in the switch
chamber 6 and be there secured by the hold-
ing screws 35. Any suitable means for es-
tablishing connection between the rod and
the mechanical actuating device may be
15 provided as for instance a group of nuts 55
screwing on the threaded end of the rod.
This method of attachment permits adjust-
ment of the attaching connections to the
needs of the particular installation without
20 altering the position of the switch body on
its support 7.

Various modifications of the structure and
in the arrangement of parts will readily oc-
cur to those dealing with the problem, with-
25 out departing from what I claim as my in-
vention.

I claim—

1. In an electric switch, an insulating
switch base recessed to afford a switch cham-
ber, a switch mechanism arranged therein
30 on an axis at right angles to the supporting
face of said base, and an operating mem-
ber extending through the side of said switch
base into operative association with the
switch mechanism.

2. In an electric switch, an insulating
switch base recessed to afford a switch cham-
ber, a switch mechanism arranged therein on
an axis at right angles to the supporting
40 face of said base, and an operating member
extending through the side of said switch
base into operative association with the
switch mechanism, together with a wire en-

try aperture opening through the opposite
side of said base, and wire terminals ar-
ranged on opposite sides of said switch cham-
ber, together with channels leading there-
from to the entry aperture. 45

3. An electric switch, comprising an in-
sulating base recessed from its upper face 50
to afford a switch chamber, a switch mecha-
nism arranged therein on an axis at right
angles to the supporting face of the base, a
lateral actuating member piercing the side
55 of the base and operatively associated with
the switch mechanism within said chamber,
in combination with a cover plate overlying
the switch chamber, and means for secur-
ing said plate in position to close the switch
chamber against the entry of foreign mat-
ter. 60

4. In an electric switch, a base recessed
from its upper face to afford a switch cham-
ber, a marginal flange on the upper face
65 of the base, and a cover piece overlying the
switch chamber and set flush with said flange,
means for securing the same to the base, said
cover comprising a metallic sheet of an out-
line corresponding to the base, and an in-
70 sulating lining for the inner face of said
cover.

5. In an electric switch, an insulating base
recessed from its upper face to afford a
switch chamber, a switch mechanism ar-
ranged therein, and comprising a rocker 75
bar, a rod operatively connected to said rock-
er bar to one side of its axis of oscillation,
and passing through the side of the base in
assembled position, said base being slotted
80 to permit said switch mechanism and actu-
ating rod to be assembled as a unit on the
base.

In testimony whereof I have signed my
name to this specification.

GEORGE B. THOMAS.
